SLEEVE VALVE FOR A FOUR STROKE OPPOSED PISTON ENGINE

Ernst Schmid, Annecy, Haute-Savoie, France

Application January 22, 1936, Serial No. 60,288
In Germany February 5, 1935

6 Claims. (Cl. 123—51)

My invention relates to improvements in a sleeve valve for a four-stroke opposed piston engine; and the objects of my improvement are, first, to prevent the piston rings from raking the ports of the valve, and, second, to prevent the piston rings from getting stuck fast to the valve ports.

I attain these objects by providing the valve with ports all lying at the same height and have it move only between the runways of the two sets of piston rings; all of which becomes evident from the accompanying drawing, in which—

Fig. 1 is a vertical section of a twin-cylinder; Fig. 2 shows the position of the sleeve valve, in

15 vertical section, during the moment of exhaust;

Fig. 3 shows the position of the sleeve valve, in vertical section, during the moment of explosion; and

Fig. 4 shows the initial position of the sleeve valve, in vertical section.

1 and 2 are two cylinders lying in line and opposite and being rigidly interconnected, in which the pistons 3 and 4 provided with sealing rings 5 are being operated in opposite sense by 25 crankshafts 6. 7 is the place of explosion common to both cylinders 1 and 2 (Fig. 3). Between the cylinder walls and the pistons we have a thin-walled sleeve valve 8 being subjected to an 30 unequally oscillating movement, in a well-known manner, by way of drive 10. 11 is the intake and 12 the exhaust. 13 and 14 are the spark plugs. The sleeve valve 8 possesses in its 35 middle a sole series of ports 15 with which the steering of intake 11 and exhaust 12 is effected. The edges 17 of ports 15 extending at right angles to the cylinder axis lie outside that part 40 of the inner cylinder wall which is raked by pistons 3 and 4 (Figs. 2—4) so that a sticking fast of the piston rings 5 to ports 15 cannot take 45 place. In order to seal the valve by means of the inside pressure at the time of compression, edges 17 of ports 15 are provided with slits 16. Since the pistons move in opposite directions, all lateral pressures of the pistons against valve 8 50 are eliminated, which latter circumstance proves to be of substantial advantage.

Besides the advantages referred to my invention has yet the advantage that the ports may receive relatively large cross-sections and this 55 so much more as each of the two edges 17 either steers the exhaust or the intake. The structural realization of my design furthermore is very simple.

I claim:

1. In an internal combustion engine of the

four-stroke opposed piston type the combination comprising a cylinder having axially spaced inlet and exhaust ports, a sleeve valve having a port in a single plane slidable axially within said cylinder, said port in said valve alternately permitting communication between said inlet and exhaust ports to the interior of said sleeve valve, pistons reciprocating in opposed directions within said sleeve valve, piston rings on said pistons and said port in said valve being so positioned that it remains always between said piston rings and is not wiped thereby.

2. In an internal combustion engine of the four-stroke opposed piston type the combination comprising a cylinder having axially spaced inlet and exhaust ports, a sleeve valve having a port in a single plane slidable axially within said cylinder, said port in said valve alternately permitting communication between said inlet and exhaust ports to the interior of said sleeve valve, pistons reciprocating in opposed directions within said sleeve valve, and a spark plug located in said cylinder wall intermediate said exhaust and inlet ports and adapted to be uncovered by said sleeve valve port.

3. In an internal combustion engine of the four-stroke opposed piston type the combination comprising a cylinder having axially spaced inlet and exhaust ports, a sleeve valve having a series of ports in a single plane slidable axially within said cylinder, said ports in said valve alternately permitting communication between said inlet and exhaust ports to the interior of said sleeve valve, pistons reciprocating in opposed directions within said sleeve valve, piston rings on said pistons, said ports in said valve being so positioned that they remain between said piston rings and are not wiped thereby, and spark plugs located in said cylinder wall intermediate said exhaust and inlet ports and said spark plugs being adapted to be uncovered by said sleeve valve ports.

4. In an internal combustion engine of the four-stroke opposed piston type, the combination comprising a common cylinder having the same inner cross section throughout and having axially spaced inlet and exhaust ports, a sleeve valve having a port in a single plane adapted to cooperate with said inlet and exhaust ports, said sleeve valve being slidable axially within said cylinder, said port in said valve alternately permitting communication between said inlet and exhaust ports to the interior of said sleeve valve, pistons reciprocating in opposed directions within said sleeve valve, piston rings on said pistons,

and said port in said valve being so positioned that it always remains between said piston rings and is not wiped thereby.

- 5 5. In an internal combustion engine of the four stroke opposed piston type, the combination comprising a common cylinder having the same inner cross section throughout and having axially spaced inlet and exhaust ports, a sleeve valve having a port in a single plane adapted to cooperate with said inlet and exhaust ports, said sleeve valve being slideable axially within said cylinder, said port in said valve alternately permitting communication between said inlet and exhaust ports to the interior of said sleeve valve, 10 pistons reciprocating in opposed directions within said sleeve valve, and a spark plug located in said cylinder wall intermediate said exhaust and inlet ports and adapted to be uncovered by the same sleeve valve port which cooperates with the 15 inlet and exhaust ports.
- 10 15 20 6. In an internal combustion engine of the

four-stroke opposed piston type, the combination comprising a common cylinder having the same inner cross section throughout and having axially spaced inlet and exhaust ports, a sleeve valve having a series of ports in a single plane 5 adapted to cooperate with said inlet and exhaust ports, said sleeve valve being slideable axially within said cylinder, said ports in said valve alternately permitting communication between said inlet and exhaust ports to the interior of 10 said sleeve valve, pistons reciprocating in opposed directions within said sleeve valve, piston rings on said pistons, said ports in said valve being so positioned that they remain between said piston rings and are not wiped thereby, and 15 spark plugs located in said cylinder wall intermediate said exhaust and inlet ports and said spark plugs being adapted to be uncovered by the same sleeve valve ports which cooperate with the inlet and exhaust ports.
